UNITED STATES PATENT OFFICE.

WILLIAM T. LAKIN, OF LONG, MARYLAND.

SOUND-BOX MOUNTING.

1,301,458.

Specification of Letters Patent. Patented Apr. 22, 1919.

Application filed January 8, 1918. Serial No. 210,873.

To all whom it may concern:

Be it known that I, WILLIAM TROUPE LAKIN, a citizen of the United States, and a resident of Long, Allegany county, Maryland, have invented a new and useful Improvement in Sound-Box Mountings, of which the following is a specification.

My invention relates to improvements in phonographic tone arms, and it consists in the constructions, combinations, and arrangements herein described and claimed.

An object of my invention is to provide a tone arm including as one of the essential features a conduit, so mounted upon the end of the tone arm as to be capable of being swung completely back out of the way, making the turn table accessible for the placing and removing of the records.

Another object of the invention is to provide a tone arm, including a reproducer neck, adjustably mounted upon the end of the sound conduit, making the reproducer adaptable to both vertically cut and laterally cut records.

Another object of the invention resides in the manner of pivotally supporting the tone arm and of affording also a continuous unbroken tone passage.

Other objects and advantages will appear in the following specification, reference being had to the accompanying drawings in which:

Figure 1, is a plan view of the tone arm.

Fig. 2, is a detail cross section of the sound conduit mounting on the tone arm.

Fig. 3, is a detail section of a portion of the mounting.

Fig. 4, is a detail section of the coupling connecting the reproducer to the reproducer neck.

Figs. 5 and 6 are face views of the opposing portions of the sound conduit mounting.

Fig. 7, is a side elevation of the parts shown in Fig. 1, portions being shown in sections.

Figs. 8 and 9 are detail views of a portion of the reproducer neck, and

Figs. 10 to 12 inclusive, are detail views of several modifications of bearing pins hereinafter described.

In my invention I provide the swinging tone arm 1, which swings horizontally over the top of cabinet 2. The large end of the tone arm 1 has a pivotal mounting on the end of the fixed tone arm 3 which is concealed in the cabinet 2 and terminates in a

horn or some other sound amplifying device. The tone arm 3 usually connects with a wood horn which terminates at a latticed front of the cabinet, but this feature having no connection with the invention need not be dwelt upon here.

Upon the end of the swinging tone arm 1, is a sound conduit 4 which, together with the reproducer neck 5 carried thereby, forms a substantially S-shaped end member. The sound conduit 4 is capable of being turned through an arc of approximately 180°. The ability to turn the sound conduit back into the dotted line position indicated in Fig. 7, facilitates the placing and removal of records on and from the turn table 6. A reproducer 7 is carried by the reproducer neck 5, and is mounted on the neck by means of a novel pivotal coupling illustrated more clearly in Fig. 4.

The pivotal mounting of the sound conduit 4 on the tone arm 1, consists of a pair of plates formed by flaring the ends of the respective members, and securing the flared plates together as will presently appear. A plate 8 is formed integrally on the end of the sound conduit 4, and the periphery of the plate 8 may be slightly curved at 9 in order that it may be encompassed by the curved periphery 10 of the plate 11, also integrally formed on the end of the tone arm 1. Obviously the plates 8 and 11 may be made separate members and secured upon the respective ends of the sound conduit 4 on the tone arm 1. It is preferable however, to flare or expand the ends of these members into the shape of the plates, thereby providing unitary structures.

A considerable space between the opposing surfaces of the plates 8 and 11 is shown in Fig. 2. In actual practice these plates will be so formed as to come very close together, consequently materially reducing the thickness of the coupling between the sound conduit and the tone arm. Ball bearings 12 are disposed between the plates. The plate 8 has a ball race 13 in which the balls run, and the plate 11 has a cone 14 which engages the balls.

The cone 14 includes an extension which fits into the adjacent point of the throat of the sound conduit to prevent the escape of sound. Attention is directed to Fig. 3. Here it will be seen that a throat 15 projects into the flared mouth 16 at the end of the sound conduit 4. It will also be observed

that the outer surface of the throat 15 is tapered so as to closely fit the flared mouth 16. It will be readily understood that the throat and the surface of the mouth will 5 be very close together, and so it can be readily understood, that the escape of sound around the joint between the two members, will effectually be prevented. As an incidental feature of construction, the throat 10 15 and the flared end 16 of the sound conduit are so fitted together that the bore of the one forms a substantial continuation of the bore of the other. Instead of forming the cone 14 and the ball race 13 on the tone 15 arm and sound conduit respectively, the location of these parts may be reversed, and may also be so modified in construction to conform to any particular requirements and still retain the essential features just 20 described and illustrated in the drawing.

Stud pins 17 and 18, upon which lock nuts 19 and 20 are threaded hold the plates 8 and 11 together. The base of each of the pins is fixed in one of the plates. Attention 25 is directed to Fig. 2. Here it will be seen that the stud pin 18 is threaded on the extremity while the base of the pin is smooth and fixed in the plate 11. The pin 18 projects through a slot 21 in the plate 8. Similarly, the stud pin 17 fits in the plate 8 and projects through a slot 22 in the plate 11.

These slots are arcuate as shown in Figs. 5 and 6 and are disposed concentrically to the tone arm and sound conduit at the point 30 of connection of these members. The arcuate formation of the slots 21 and 22 is shown in Figs. 5 and 6. It will therefore be observed that the respective pins 17 and 18 stand on the base of each of the slots. In 35 fitting the plates 8 and 11 together, the pins are made to project through the companion slot of each of the plates, whereupon the plates are secured together by means of the lock nuts as will presently more fully appear. The pins 17 and 18 are also adapted to abut the other end of each of the other 40 slots in which the respective pins play, and thus limit the backward and forward motion of the sound conduit.

Washers 23 are screwed upon the threaded 50 ends of the respective pins and precede the lock nuts 19 and 20. The washers 23 are screwed only far enough down on the pins to secure freedom of rotational movement 55 of the sound conduit on the tone arm, and are so adjusted on the pins that lateral motion on the tone arm 1 is prevented. The lock nuts 19 and 20 then follow, and are screwed tightly against the washers. It 60 will be observed that the edge of the plate 11 is curled or curved more than is the edge 19 of the plate 8. The edge of the curved portion of the plate 11 is slightly restricted so that it may snap over the edge of the 65 plate 8 and form a tight joint between the

plates. This arrangement is clearly illustrated in Fig. 2. Here it will also be seen that the outer surface of the curved edge 10 is knurled principally to give the coupling a more pleasing appearance.

The reproducer neck 5 is radially adjustable upon the end of the sound conduit 4 by the means illustrated in Figs. 8 and 9. A set screw 24 is screwed into the open end 75 of the sound conduit 4 at one side. The elbow of the reproducer neck 5 has an annular groove 25 adjacent to the end thereof, with an inlet 26 which permits the introduction of the end of the set screw 24 into the groove 25 by unscrewing the screw 24 until 80 the end of the screw comes flush with the bore of the sound conduit. A plurality of openings 27 are formed in the groove 25. These openings are smooth, and when the desired adjustment of the reproducer neck 85 size is obtained, the set screw 24 is simply turned into engagement with the proper one of the openings 27, whereupon the adjustment is held as clearly illustrated in 90 Figs. 1 and 9.

The reproducer neck 5 may be disposed in either the right or left hand positions indicated in Fig. 1 or in the central position with the diaphragm of the reproducer downward and parallel to the turntable. The adjustments in the first two instances indicated A and B are where the reproducer is employed on laterally undulating records, and the adjustment in the second instance C is where the reproducer is employed on perpendicularly cut records. The intermediate holes or openings 27 simply provide an additional range of adjustment and may be employed as needed or discarded altogether.

The compression coupling between the reproducer 7 and the reproducer neck 5, previously mentioned, includes a plurality of rubber gaskets 28 concealed in a cup 29, and encircling the free end of the reproducer neck 5 as clearly shown in Fig. 4. The free 105 end of the neck is split at 30. The gaskets 28 are compressed by means of the compression screws 31 which pass through the gaskets and are threaded into the back of the reproducer 7. The edge of the cup 29 is 110 slightly spaced from the back plate of the reproducer in order to give the screws 31 a certain amount of movement wherein the rubber gaskets 28 are compressed and consequently expanded against the free end of the 115 neck 5. This compression coupling not only serves to hold the reproducer firmly in position on the end of the neck, but also permits the radial adjustment of the reproducer 120 on the end of the neck, since the reproducer may be readily turned on exerting a little pressure to overcome the friction between the expanded gaskets on the end of the neck.

Another important feature of the invention resides in the pivotal mounting of the 125

swinging tone arm 1 on the tone arm 3. Attention is directed to Fig. 7. A standard 32 is mounted on a bracket 33, directly in the center of the vertical portion of the elbow. 5 The standard 32 has a reduced portion at the top providing a shoulder 34 upon which the bridge 35 of the tone arm 1 rests. The standard is centrally threaded to receive the threaded reduced end of a stabilizing 10 pin 35^a.

The pin 35^a tapers slightly. The pin has a cone bearing 36 near the top, which terminates in a threaded shank 37 surmounted by a head 38. The cone bearing 36 engages a 15 conical recess 39 in the top wall of the tone arm. The threaded shank 37 screws into a threaded opening in the horizontal portion of an arm 40. The arm 40 is an extension of the bracket 33 on which the standard 32 is mounted. The bracket 33 is introduced into the channel of the tone arm through an opening 41, the adjacent portion of the bracket 33 being wrapped with rubber 42 in order to prevent any rattling that might 25 ensue by the contact of the metallic portion of the bracket and the tone arm. The bracket and the arm 40 are secured in place on the stationary tone arm 3 by the screws illustrated, or by some other suitable means.

30 Glycerin, vaseline, or some other suitable sealing material is placed in an annular channel 43 formed on the upper edge of the tone arm 3, which receives the end of the tone arm 1. It will be understood that the 35 end of the elbow of the tone arm 1, runs in the channel 43 and the sealing material which fills the remainder of the channel, prevents the escape of sound around the joint between the two members of the tone arm. 40 As stated above, this sealing material may consist of any suitable substance, such for instance as glycerin, vaseline, etc.

An iris diaphragm 44 is located in the stationary tone arm 3, but more properly, at 45 the union of the stationary tone arm and the amplifying horn within the cabinet. The diaphragm has a lever 45 projecting out at one side, and by means of which the diaphragm may be opened or closed to regulate 50 the volume of sound passing into the stationary amplifying horn or trumpet.

The operation of the device will be readily understood from the foregoing description when taken in connection with the following additional explanation. The tone arm 1 swings in a horizontal direction over the top of the cabinet 2 and over a portion of the turn table 6, while the continuation of the tone arm inside of the cabinet is stationary and terminates in some sound amplifying device, as for instance a horn. The manner of pivotally mounting the swinging tone arm 1 on the stationary portion of the tone arm, constitutes one of the important 65 features of the invention. The manner of

assembling the swinging tone arm 1 on the stationary tone arm will be readily understood. It should be observed that the distance between the uppermost portion of the tone arm 1 and the under surface of the 70 horizontal portion of the arm 40 is the same as the distance between the shoulder 34 and the upper surface of the reduced portion of the standard 32. The reason for this arrangement will readily be seen. The elbow 75 of the tone arm 1 is inserted over the end of the standard until the bridge 35 rests on the shoulder 34. In order to be able to do this, the respective distances just described must be the same in order to enable the placing 80 of the elbow beneath the horizontal portion of the arm 40.

The tone arm having been put in place, is held in position until the stabilizing pin 35^a is screwed in place, whereupon the tone 85 arm 1 is supported by the cone bearings 36 and 39 at the top and the shoulder 34 of the standard 32, at the bottom. The diameters of the various portions of the stabilizing pin 35^a, decrease from the head 38 to the 90 pit of the pin. This structural feature of the pin of course permits the insertion of the pin through the opening in the arm 20 until the threaded extremity of the pin is screwed into the standard 32. The shoulder 95 adjacent to the threaded extremity of the pin eventually binds against the top surface of the standard, and the cone bearing 36 will be found to be in proper position in the conical opening 39 in the tone arm, so 100 that a mounting for the tone arm is provided which holds the tone arm securely in position and at the same time prevents rattling and lateral motion of the tone arm on the stabilizing pin. 105

The pivotal coupling of the sound conduit 4 on the tone arm 1, is of such a nature that the sound conduit may be swung back through approximately an arc of 180° to get the reproducer out of the way and permit the ready placing or removal of a record on and from the turn table. This feature is one of the most important of the whole invention. The manner of forming the pivotal coupling is thought to be fully understood. Briefly, however, it consists of the pins 17 and 18 fixed on the respective plates 8 and 11, which project through a companion arcuate slot 21 and 22 in the respective plates. Washers 23 are screwed upon the threaded ends of the pins until the ball bearings 12 in the ball race 13 and pressed on tightly enough to prevent rattling and still secure easy movement of the sound conduit on the tone arm. The lock nuts 19 and 20 are then screwed into position, whereupon the coupling is ready for use. Although it matters little in which location the respective stud pins are mounted on the respective plates, it should be observed that 125 130

when they are so arranged that the binding nut 19 is tightly secured in the crook of the tone arm 1, and the lock nut 20 is tightly inclosed in the crook of the sound conduit 4, these nuts are out of the way as it were and the possibility of striking there against is materially reduced.

The construction of the compressed coupling and the manner of securing the radial 10 adjustment of the reproducer neck 5 on the sound conduit 4, are features which are thought to be understood. The compression coupling consists of a plurality of rubber gaskets which are compressed against the 15 end of the reproducer neck, by screwing down the compression screw 31. The slight space between the edge of the cup 29 which houses the rubber gaskets, and the adjacent surface of the back plate of the reproducer, 20 permits the screws to be moved through this distance and the gaskets to be compressed accordingly.

The back of the reproducer 7 is preferably provided with an annular flange 25 into which the edge of the cup 29 fits, as shown in Fig. 4.

Figs. 10 to 12 inclusive illustrate certain modifications of more or less flexible bearing pins to be used in connection with the 30 reproducer 7. These bearing pins have for their object, the holding of the needle bar 54 in place. These pins are supported in brackets 53 and are so arranged that by their 35 resiliency, a freer rocking motion of the needle bar is obtained. Fig. 10 illustrates a pin composed of two parts 46 and 47. The part 46 has a right hand thread and is extended at 48 and has a left hand thread. The extension 48 screws into a threaded 40 socket 49. The portion 47 is cut away or flattened at 50 so that the bearing pins may be more resilient. The pins in Figs. 11 and 12 are also reduced in the middle. The one shown in Fig. 11 is similar in appearance 45 to the portion 47, with the exception that the head 51 is threaded. The central portion of the pin in Fig. 12 is cylindrically constricted at 52, this constriction also being for the purpose of giving the stylus bar 50 added resiliency and increasing its sensitiveness.

While the construction and arrangement 55 in an integral coupling member, a sound company drawings is that of a generally preferred form, obviously modifications and changes may be made without departing from the spirit of the invention or the scope of the claims.

I claim,

60 1. A tone arm having a bent end terminating in an integral coupling member, a sound conduit having a coöperating coupling member at one end applied to said tone arm coupling member and being curved to place the 65 axis of the open end of the sound conduit at

right angles to the axis of the end of the coupling, a reproducer neck radially adjustable in said open end and in a plane parallel to the axis of the coupling, and a radially adjustable reproducer mounted on the end 70 of said neck.

2. A tone arm comprising a sound conduit having a set screw, and a reproducer neck including an elbow having an annular slot with an entrance opening directed toward the opening of the elbow to admit the point of the set screw into the slot in assembling the parts, and a plurality of unthreaded apertures in the bottom of the slot for receiving the point of the set screw when the 75 set screw is screwed in place.

3. A tone arm having one end flared to form a plate, a sound conduit having one end flared to form a coöperating plate, the edges of the plates being shaped to snap together, 85 bearing means mounted between the plates, means carried by each plate engaging in the companion plate to limit the rotational movement of the sound conduit on the tone arm, adjusting means carried by said engaging means to regulate the pressure on said 90 bearings, and locking means on said engaging means for binding on said adjusting means.

4. A tone arm having one end flared to 95 form a plate with a slot, a sound conduit having one end flared to form a companion plate with a slot, the edges of said plates being shaped to snap one upon the other, pins carried by the plates engaging in the 100 companion slots, bearing devices mounted between the plates, a washer threaded upon each pin to adjust the pressure on said bearings, and lock nuts following said washers and said pins.

5. A tone arm having a flared end to form a plate having an arcuate slot, having a flared end providing a companion end having an arcuate slot, the edges of said plate being curved and arranged to snap one in 110 the other, a ball race formed on the sound conduit, a bearing cone formed on the tone arm, bearings disposed between said cone and said race, a portion of the cone extending into the adjacent portion of the sound 115 conduit to prevent the escape of sound, a pin mounted on each plate and projecting into the companion slot, a washer threaded on each pin, and a lock nut following each washer.

6. A tone arm having a crook curved in one direction and terminating in a coupling plate, a sound conduit having a crook curved in the opposite direction and terminating in a coupling plate, bearing means located between the plates, and means holding the plates together including lock nuts located in the respective crooks, said lock nuts being thus shielded.

7. A tone arm, a reproducer neck having 120

- a split end, a reproducer mounted on the neck, a cup having the edge normally spaced from the back plate of the reproducer, compressible means located in the cup engaging 5 the split end of said neck, and means passing through the cup and said compressible means into said back plate, for compressing said compressible means and expanding it against said neck.
- 10 8. A reproducer mounting including coupling plates each carrying interengageable portions arranged to snap together in as- sembling the coupling, bearing means located between said coupling plates and keeping the plates spaced apart, and means carried by 15 each of the plates and extending through the companion plate enabling the regulation of the pressure of the plates on said bearing means.
